ENCLOSED CIRCUIT BREAKER

John G. Jackson, Detroit, Mich., assignor to
Square D Company, Detroit, Mich., a corpora-
tion of Michigan

Application July 1, 1935, Serial No. 29,277

15 Claims. (CL 200—50)

This invention relates to enclosed automatic electric circuit breakers and has for its object the provision of an improved enclosure for circuit breakers.

5 Another object of this invention is to provide an enclosed automatic circuit breaker with a pivotal mounting providing for swinging movement to the exterior of the enclosing box.

Another object of this invention is to provide 10 an enclosed automatic circuit breaker with an improved operating member.

Another object of this invention is to provide 15 an enclosed automatic circuit breaker having a front operating handle with an operating member engaging said handle at all times to prevent damage thereto.

Another object of this invention is to provide 20 a swingable mounting for an enclosed automatic circuit breaker with an improved interlock construction.

Other objects and features of this invention will be readily apparent to those skilled in the art from the following specification and appended drawing illustrating certain preferred embodiments 25 of the invention. This invention is a continuation in part of my copending application, Serial No. 765,265, filed November 30, 1934.

In the drawing:

Figure 1 is a front elevational view of an 30 enclosed circuit breaker according to the present invention with the cover broken away to show internal parts.

Figure 2 is a sectional view on the line II—II of Figure 1.

35 Figure 3 is an enlarged detail view on the line III—III of Figure 1 showing the interlock mechanism.

Figure 4 is a detail view of the interlock with the cover open.

40 Figure 5 is a detail sectional view of the interlock mounting taken on the line V—V of Figure 1.

The circuit breaker enclosure, according to the present invention, embodies a box 1 having a cover 2 pivotally mounted thereon as at 3. Within the box is disposed a U-shaped saddle or strap 4 pivotally mounted as at 5 to the box wall. The saddle 4 is spaced from the back wall of the box 1 and extends thereacross into engagement with the opposite side of the box. A circuit breaker 6 is rigidly mounted on the saddle 4. This circuit breaker may be of any conventional form and is here shown as a sealable circuit breaker having a front operated handle 7. A crank 8 is pivotally 50 mounted in the opposite sides of the saddle 4 and

extends across the front of the breaker and carries a part 9 engaging the breaker handle 7. This part 9 may be U-shaped and extend through parallel slots in the crank 8, being held therein by stud 11 with the legs of the U disposed on opposite sides of the handle 7. A side operating handle 12 is mounted on the free side of the saddle 4 and has operative connection to crank 8. It is, of course, obvious that the crank 8 and handle 12 may be integral.

The box wall is provided with a slot which receives the handle 12 and a stud 13 also mounted on the saddle 4. The stud 13 when tightened down will secure the saddle 4 within the box 1, the side of the saddle then serving to seal the slot in the box wall.

10 A spring pressed latch 14 is mounted on the box wall and extends through a slot in the cover 2 to latch it in closed position.

An interlock to prevent operation of the breaker to "on" position while the cover is open and to prevent opening of the cover while the breaker is "on" is provided. This embodies a part 15 movable with the saddle 4 and rigidly interconnected with the handle 12 and crank 8. A second part 16 is pivotally mounted on the box wall and is spring pressed as by the spring 17 toward the part 15. A third part 18 of the interlock is rigidly secured to the cover and is adapted to engage the part 16 and swing it away from the part 15 when the cover is in closed position. This swinging movement of the part 16 swings a latching portion 19 into engagement with a hook 21 on the part 18. When the breaker is in "off" position in the position shown in Figure 3, the opening movement of the cover permits the member 16 to swing clockwise from the position there shown to disengage the latch 19 from the hook 21. However, when the breaker is moved to "on" position the part 15 will be rotated counterclockwise to a position opposite the surface 22 on the part 16, whereupon the described swinging movement to release the cover will be prevented and the cover locked in position. When the cover is opened the interlock parts assume the position shown in Figure 4 with the part 16 engaged with part 15 to prevent movement of the operating handle toward "on" position. The swinging movement of the part 16 is limited to the position shown in Figure 4 by a stop 23 on the box wall.

It is thus seen that the saddle 4 and its associated parts including the handle 12 and the interlock part 15 may be swung to the exterior of the box when the cover is opened to uncover the box

interior and that when the saddle is swung back within the box the interlock parts 15 and 16 will be properly engaged. This pivotal mounting for the circuit breaker is particularly adapted for ease 5 in wiring as with the saddle spaced from the back wall of the box (as more particularly shown in Figure 2) to provide a wiring space, the screw 13 may be loosened and the saddle and its associated parts flipped to the exterior of the box, 10 whereupon the wires may be drawn into the box interior and the saddle then readily swung back into the box and the stud 13 tightened to hold the breaker in position within the box.

It is to be noted that the crank 8 always extends 15 in front of the breaker with its part 9 always in engagement with the handle 7 to prevent damage thereto.

To facilitate the swinging movement of the saddle 4 to the box exterior, the corner thereof 20 remote from the pivotal mounting 5 is provided with a chamfered portion 24 which may be in the form of a rounded curve if desired.

While certain preferred embodiments of the invention have been specifically disclosed, it is 25 understood that the invention is not limited thereto as many variations will be readily apparent to those skilled in the art and the invention is to be given its broadest possible interpretation within the terms of the following claims:

30 What is claimed is:

1. In an enclosed circuit breaker, an enclosing box, a cover for said box, a circuit breaker mounted in said box and comprising automatically and manually operable electric circuit breaker mechanism, an enclosure for said mechanism and an operating handle extending through the enclosure, an operating member rotatably mounted on said box, said member having a portion extending over said circuit breaker and carrying a part 35 engaging said handle, said member having a portion extending exteriorly of the box wall and constituting an outside operating handle, said part comprising a removable element having spaced, 40 depending legs disposed on opposite sides of said circuit breaker handle without positive connection thereto and operating to move the same in response to movement of said operating member.

2. In an enclosed circuit breaker, an enclosing box, a cover for said box, a circuit breaker mounted in said box and comprising automatically and manually operable electric circuit breaker mechanism, an enclosure for said mechanism and an operating handle extending through the enclosure, a crank rotatably supported on opposite 45 walls of said box and having a portion extending over said circuit breaker, said portion carrying a part engaging said circuit breaker handle, and an outside operating handle mounted on said box and having operative connection with said crank, said part comprising a generally U-shaped element 50 removably mounted on said portion and having its legs disposed on opposite sides of said circuit breaker handle.

3. In an enclosed circuit breaker, an enclosing box, a cover for said box, a supporting member pivotally mounted in said box for swinging movement to the exterior thereof while attached to and supported on the box, a circuit breaker mounted on said member and comprising automatically and manually operable electric circuit breaker mechanism, an enclosure for said mechanism and an operating handle extending through the enclosure, an operating element rotatably mounted on said member and having a portion extending over said breaker and carrying means en- 55

gaging said handle, said element having another portion on the exterior of said box and serving as an outside operating handle.

4. In an enclosed circuit breaker, an enclosing box, a cover for said box, a supporting member pivotally mounted in said box, a circuit breaker mounted on said member and comprising automatically and manually operable electric circuit breaker mechanism, an enclosure for said mechanism and an operating handle extending through the enclosure, an operating element rotatably mounted on said member and having a portion extending over said breaker and carrying means engaging said handle, said element having another portion on the exterior of said box and serving as an outside operating handle, said member, breaker, and element being bodily swingable to the exterior of the box, while being attached to and supported on the box when the cover is open. 20

5. In an enclosed circuit breaker, an enclosing box, a cover for said box, a supporting member pivotally mounted in said box for swinging movement to the exterior thereof while attached to and supported on the box, a circuit breaker mounted on said member and comprising automatically and manually operable electric circuit breaker mechanism, an enclosure for said mechanism and an operating handle extending through the enclosure, an operating element rotatably mounted on said member and having a portion extending over said breaker and carrying means engaging said handle, said element having another portion on the exterior of said box and serving as an outside operating handle, said second portion extending through a slot in the box wall to permit swinging of the member and its supported elements to the exterior of the box. 30

6. In an enclosed circuit breaker, an enclosing box, a cover for said box, a supporting member pivotally mounted in said box for swinging movement to the exterior thereof while attached to and supported on the box and spaced at least in part from the rear wall of the box, a circuit breaker mounted on said member and comprising automatically and manually operable electric circuit breaker mechanism, an enclosure for said mechanism and an operating handle extending through the enclosure, a crank pivotally mounted on said member, said crank extending over said circuit breaker and carrying a part engaging said handle, and an outside operating handle mounted on said member and having an operating connection with said crank. 40

7. In an enclosed circuit breaker, an enclosing box, a cover for said box, a supporting member pivotally mounted in said box for swinging movement to the exterior thereof while attached to and supported on the box, a circuit breaker mounted on said member and comprising automatically and manually operable electric circuit breaker mechanism, an enclosure for said mechanism and an operating handle extending through the front of the enclosure, a crank rotatably mounted on said member and extending over the front of said breaker and carrying a part engaging said handle, and an outside operating handle having operative connection with said crank. 50

8. In an enclosed circuit breaker, an enclosing box, a cover for said box, a supporting member pivotally mounted in said box for swinging movement to the exterior thereof while attached to and supported on the box, a circuit breaker mounted on said member and comprising automatically 60

- and manually operable electric circuit breaker mechanism, an enclosure for said mechanism and an operating handle extending through the front of the enclosure, a crank rotatably mounted on 5 said member and extending over the front of said breaker and carrying a part engaging said handle, and an outside operating handle having operative connection with said crank, said member being provided with a clearance portion remote from the 10 pivotal mounting to provide for swinging movement to the box exterior.
9. In an enclosed circuit breaker, an enclosing box, a cover for said box, a supporting member pivotally mounted in said box for swinging movement to the exterior thereof while supported on 15 the box, a circuit breaker mounted on said member and comprising automatically and manually operable electric circuit breaker mechanism, an enclosure for said mechanism and an operating 20 handle extending through the enclosure, an operating element rotatably mounted on said member and having a portion extending over said breaker and carrying means engaging said handle, said element having another portion on the exterior of 25 said box and serving as an outside operating handle, and an interlock comprising a part movable with said element, a second part mounted on the box wall and a third part carried by the cover, said first part being swingable with the 30 member to the box exterior and readily engaging and disengaging with the second part.
10. In an enclosed circuit breaker, an enclosing box, a cover for said box, a U-shaped saddle disposed in said box with the base of the U spaced 35 from the back wall of the box, a circuit breaker mounted on said saddle and comprising automatically and manually operable electric circuit breaker mechanism, an enclosure for said mechanism and an operating handle extending through 40 the front of the enclosure, and an operating member rotatably mounted on said saddle and having a portion extending over said breaker and carrying a part engaging said handle, said member extending to the exterior of the box and 45 terminating in an operating handle.
11. In an enclosed circuit breaker, an enclosing box, a cover for said box, a U-shaped saddle pivotally mounted in said box, a circuit breaker mounted on said saddle and comprising automatically and manually operable electric circuit breaker mechanism, an enclosure for said mechanism and an operating handle extending through 50 the front of the enclosure, a crank rotatably mounted on said saddle and extending over the front of said breaker and carrying a part engaging said handle, an outside operating handle mounted on said 55 box and having operative connection with said crank, said saddle and its associated parts being bodily swingable to the box exterior, said crank extending over said breaker and engaging the breaker handle through said part at all times to protect said breaker handle against damage.
12. In an industrial type circuit breaker, an enclosing box, a cover for said box, a U-shaped saddle disposed in said box with the base of the U spaced from the back wall of the box, a circuit breaker having a front operating handle mounted on said saddle and an operating member rotatably mounted on said saddle and having a portion extending over said breaker and carrying a part engaging said handle, said member extending to the exterior of the box and terminating in an operating handle, said saddle being pivotally mounted within said box and having a clearance portion remote from said pivot to provide for swinging movement to the exterior of said box. 16
13. In an enclosed circuit breaker, an enclosing box, a cover for said box, a U-shaped saddle disposed in said box with the base of the U spaced from the back wall of the box, a circuit breaker having a front operating handle mounted on said saddle and an operating member rotatably mounted on said saddle and having a portion extending over said breaker and carrying a part engaging said handle, said member extending to the exterior of the box and terminating in an operating handle, said saddle being pivotally mounted on said box with the corner thereof remote from said pivot chamfered to provide clearance for swinging movement of the saddle. 18
14. In an enclosed circuit breaker, an enclosing box, a cover for said box, a supporting member pivotally mounted in said box for swinging movement to the exterior thereof, a circuit breaker mounted on said member and having a front operating handle, a crank rotatably mounted on said member and extending over the front of said breaker and carrying a part engaging said handle, an outside operating handle having operative connection with said crank, and an interlock comprising a part carried by said member, a second part carried by said box and a third part carried by said cover. 20
15. In an enclosed circuit breaker, an enclosing box, a cover for said box, a supporting member pivotally mounted in said box, a circuit breaker mounted on said member and having a front operating handle, a crank rotatably mounted on said member and extending over the front of said breaker and carrying means engaging said handle, an outside operating handle connected to said crank, and an interlock comprising a part rotatable with said outside handle and crank, a second part pivotally mounted on said box and a third part carried by said cover, said first and second parts being readily engageable and disengageable upon swinging movement of said member, said second part preventing rotation of said first part when the cover is open and engaging said third part to prevent opening of said cover when the breaker is closed. 25

JOHN G. JACKSON. 60
